RECOVERY OF USEFUL PRODUCT FROM SPENT DOCTOR

John B. Holtzelaw, Roselle, N. J., assignor to
Standard Oil Development Company, a corpora-
tion of Delaware

Application July 23, 1952, Serial No. 300,539

3 Claims. (Cl. 252—183)

1
The present invention is concerned with an improved process for the segregation of valuable products from a spent doctor or alkali metal plumbite solution. The invention is more particularly concerned with the processing of a spent sodium plumbite solution which has been utilized for the treatment of a petroleum fraction boiling in the motor fuel boiling range and subsequently utilized for the treatment of a petroleum fraction boiling in the heating oil boiling range. In accordance with the present invention, a spent sodium plumbite solution is treated with a sodium bisulfide solution and isopropyl alcohol.

It is well known in the art to treat mercaptan containing petroleum fractions with a sodium plumbite solution. In these processes the sodium plumbite solution converts the mercaptans to lead mercaptides which are treated with free sulfur to form disulfides and lead sulfide.

The plumbite solution is prepared by dissolving lead oxide in sodium hydroxide as follows:

Upon treatment of the oil fraction with the sodium plumbite solution the normal lead mercaptide and basic lead mercaptide are formed as follows:

Upon the addition of sulfur the relatively innocuous disulfides are formed and lead sulfide is precipitated as follows:

In these reactions the spent doctor solution is regenerated as follows:

However, in time sodium thiosulfate tends to build up in the spent doctor by the action of oxygen from the air on the sodium sulfide.

When the spent doctor from the naphtha treating operation is utilized for the treatment of 50 heating oils, sulfur is added and the solution is blown with air in a manner to convert the aromatic mercaptans to polysulfides.

The spent doctor solution withdrawn from the heating oil treatment contains an appreciable 55

quantity of thiosulfates. In accordance with the present invention, this spent solution is passed to a collecting zone wherein the same is contacted with sodium hydrogen sulfide (NaHS) and isopropyl alcohol.

The process of the present invention may be more fully understood by reference to the drawing illustrating an embodiment of the same.

Referring specifically to the drawing a petroleum fraction boiling in the motor fuel boiling range is introduced into treating zone 1 by means of feed line 2. Fresh caustic is introduced into zone 1 by means of line 3, while spent caustic is removed by means of line 4. The treated oil is removed from zone 1 by means of line 5 and introduced into doctor treating zone 6. A fresh doctor solution is introduced into zone 6 by means of line 7 while the spent doctor is removed by means of line 8. A petroleum fraction boiling in the heating oil boiling range (400 to 750° F.) is introduced into caustic treating zone 9 by means of line 10. Fresh caustic is introduced into zone 9 by means of line 11 and withdrawn by means of line 12. The treated oil is removed from zone 9 by means of line 13 and introduced into doctor treating zone 14 wherein the same is contacted with spent doctor withdrawn from zone 6. Treated motor fuel is removed from zone 6 by means of line 15 and further refined or handled as desired. Treated oil boiling in the heating oil boiling range is removed from zone 14 by means of line 16 and may also be further refined or handled as desired. In accordance with the present invention the spent doctor is withdrawn from zone 14 by means of line 17 and passed to a collecting zone 18 wherein three layers form on standing. The upper layer comprises an oil layer containing dissolved therein oil soluble lead soaps of naphthenic acids. The middle layer comprises lead sulfide, a sodium naphthenate emulsion, sodium hydroxide and water. The lower layer comprises an aqueous layer containing sodium plumbite, free caustic and sodium thiosulfate.

In accordance with the present invention, sodium bisulfide is introduced into zone 18 by means of line 19 and isopropyl alcohol by means of line 20. Under these conditions the upper oil layer is rendered substantially completely free of lead soaps. An oil layer free of lead soaps is withdrawn from zone 18 by means of line 21 and passed to distillation zone 22. Temperature and pressure conditions are adjusted in zone 22 to remove overhead by means of line 23 the alcohol. A treated oil is removed by means of line 24 and is preferably recycled to zone 9. An alcohol so-

3

lution of sodium naphthenates is removed from zone 18 by means of line 25 and passed to distillation zone 26. Temperature and pressure conditions in zone 26 are adjusted to remove overhead by means of line 27 the alcohol and to remove by means of line 28 sodium naphthenates. A bottom layer comprising sodium hydroxide, sodium sulfide and sodium thiosulfate, and a sediment of PbS is removed by means of line 29. This solution is very adaptable for the manufacturing of paper after the recovery of traces of alcohol and filtering or centrifuging to remove the PbS.

The process generally is concerned with the handling of a spent doctor solution, particularly a spent doctor solution segregated from a naphtha treating operation followed by subsequent heating oil operations. The treating agent comprises sodium bisulfide and a low molecular weight alcohol, preferably isopropyl alcohol. The amount of sodium bisulfide present may be varied appreciably in the treating solution but is preferably in the range from about 10-12% by weight. Approximately 10% by volume of spent caustic solution containing the sodium bisulfide is added to zone 18 by means of line 19. The quantity of alcohol added also may vary appreciably but is in the range from 30 to 50% by volume. The concentration of the alcohol is in the range from 90-95%.

What is claimed is:

1. Improved process for the production of a

4

solution comprising sodium sulfur salts which comprises contacting a hydrocarbon mixture containing mercaptans and boiling in the motor fuel boiling range with a doctor solution, thereafter using said doctor solution to contact a hydrocarbon mixture containing mercaptans and boiling in the heating oil boiling range, withdrawing the spent doctor and contacting the same with an alkali metal bisulfide and a low molecular weight alcohol, whereby three phases form, withdrawing the intermediate phase and distilling the same, removing alcohol overhead and removing a bottom fraction comprising sodium sulfur salts.

2. Process as defined by claim 1 wherein the bisulfide is sodium bisulfide and wherein said alcohol comprises isopropyl alcohol.

3. Process as defined by claim 2 wherein the amount of alcohol employed is from about 30 to 50% by volume based upon the volume of spent doctor solution and wherein the concentration of the alcohol is in the range from about 90 to 95%.

JOHN B. HOLTZCLAW.
